United States Patent Office

Des. 189,348
Patented Nov. 29, 1960

189,348

CHAIR

John J. Lubberts and Lambert J. Mulder, Grand Rapids,
Mich., assignors to Tomlinson of High Point, High
Point, N.C., a corporation of North Carolina

Filed Oct. 1, 1959, Ser. No. 57,763

Term of patent 14 years

(Cl. D15—1)

FIG. 1

FIG. 2

Fig. 1 is a perspective view of a chair embodying our new design; and

Fig. 2 is a front view thereof.

The back of the chair is substantially plain.

We claim:

The ornamental design for a chair, substantially as shown and described.
